FIG. 3

Walter J. Cummings
Inventor

By Herbert E. Smith

Attorney

UNITED STATES PATENT OFFICE.

WALTER J. CUMMINGS, OF STARBUCK, WASHINGTON.

CLOTHESLINE.

Application filed April 8, 1924. Serial No. 704,937.

To all whom it may concern:

Be it known that I, WALTER J. CUMMINGS, a citizen of the United States, residing at Starbuck, in Columbia County, and 5 State of Washington, have invented certain new and useful Improvements in Clotheslines, of which the following is a specification.

My present invention relates to improvements in clotheslines adapted especially for 10 indoor use as in a drying room, but also applicable for outdoor use for hanging out and drying clothes.

The primary object of the invention is 15 the provision of an appliance that is comparatively inexpensive in cost of production, which may be installed with convenience, and which may with facility be extended for use when desired. With equal 20 facility the appliance may be compactly arranged when not in use to occupy a minimum of space in a room and be out of the way, but ready at all times for immediate extension and use.

25 With these objects in view the invention consists in certain novel combinations and arrangements of parts including a one-piece continuous rope or line having its ends anchored at a single point and provided 30 with movable and adjustable carriers for holding the line in suspension, together with means for automatically taking up the slack of the line by tightening the rope.

In the accompanying drawings I have 35 illustrated one complete example of the physical embodiment of my invention wherein the parts are combined and arranged in accordance with the best mode I have thus far devised for the practical 40 application of the principles of my invention.

Figure 1 is a perspective view showing 45 the clothesline extended for use as in a drying room or other space within a house.

Figure 2 is an enlarged detail view of one 50 of the suspending pulleys and its carriage, showing in section also one of the tracks for the carriage, the pulley being shown in position for use, and in dotted lines in inoperative position.

Figure 3 is an enlarged detail view of the line tightening device.

Figure 4 is an edge view of the weighted 55 hanger of the line tightening device.

Figure 5 is a perspective view of the

anchoring bolt or screw for both ends of a single rope forming the line.

While the device of my invention is designed for both outdoor and indoor use, for convenience of illustration and description, 60 the invention is herein exemplified for indoor use, and the walls W and W' indicated in the drawings may be the side walls of any suitable room in which the clothes may be dried.

At a suitable height along the walls W and W', preferably near the ceiling of the room I install permanent channel iron plates 1 and 2, disposed horizontally on the opposite walls and located in the same horizontal plane. Each of these channel plates is fashioned with a longitudinal front groove 3 centrally thereof above and below which are formed cylindrical track ways 4 and 5.

75 These channel plates are cut to suitable length depending upon the capacity of the clothesline to be used, and are secured to the faces of the walls as by screws 6, one end of each of the channel plates being left 80 open for the introduction of line carriers or carriages as will be described.

A permanent anchoring bolt or screw 7 is also secured in one of the walls as W at a predetermined point, which bolt is provided 85 with a suitable head 8 to which both ends of a single rope or line 9 are attached or tied.

The line is preferably arranged in zig zag 90 fashion transversely of the room and suspended from line carriages indicated as a whole by the numeral 10. These carriages are arranged in sets at opposite sides of the room and are used in numbers according to the length of the rope or line, all of the 95 carriages being of similar construction and operation.

In Figure 2 one of the carriages is shown 100 in detail with a pair of spaced, horizontally disposed wheels 11 preferably having rounded treads and conforming to the interior of the cylindrical tracks 4 and 5 of the channel plates along which tracks the wheels may roll. The wheels are journaled on a vertically disposed axle 12 and the carriage is retained in upright position by the formation of the channel plate as indicated 105 in Figure 2. A suspending hanger 13 is fixed in horizontal position to the axle 12 and projects laterally through the slot 3 in 110

the channel plate. To this hanger is hinged a U-shaped pulley-yoke 14 by means of the pivot or hinge pin 15, and a pulley 16 for the rope 9 is journaled at 17 in the yoke.

- 5 When in use the pulley and its yoke are extended in horizontal position and retained in that position by means of the tightened clothes line, but when not in use, the yoke and pulley, with the line supported in the pulley, are swung by gravity to the vertical dotted line position of Fig. 2. These carriages are of course movable and may be rolled with the suspended clothesline into compact arrangement at one end of the room 10 when the line is not in use. When desired for use the carriages are rolled through their complementary tracks into spaced relationship as indicated in Figure 1 for suspending the zig zag line.
- 15 On the wall W of the room a number of guide pulleys 18 are provided, each journaled in a stationary or fixed bearing bracket 19, and the line is passed around these guide pulleys for the purpose of providing a number, (as three) of flights of 20 suitable length which afford suspending means for a gravity actuated line tightener or stretcher operative when the line is extended to hold the zig zag flights of the line 25 under tension for supporting the clothes thereon.

The line tightener is indicated as a whole by the numeral 20, and as best seen in Figure 4 it includes a vertically disposed frame 30 21 in which three superposed guide pulleys 22, 23, and 24 are journaled within the brackets 25 of the frame.

At the lower end of the frame 21 a bottom hook 26 is fashioned, and the eye 27 of a weight 28 is suspended in the hook. The weight, which may conveniently be of 35 molded concrete or similar material is of sufficient capacity not only to pull down the three flights of the rope, but also to counter-balance the weight of the clothes which are to be hung upon the zig-zag line.

When the zig zag flights of the line are

pushed to one end of the tracks the weight 40 28 descends pulling the several flights or sections of the rope or line taut across the 50 upper portion of the room, and the lowered weight takes up the slack to compensate for the minimum length of the zig zag flights. When the zig zag flights are extended for use the weight is lifted, and the added 55 weight of the clothes on the line counter-balances the weight thus maintaining the flights of the line or rope under tension for the support of the hanging clothes.

The clothes line appliance may be manipulated with facility and convenience and the disposition of the flights in combined arrangement with the weight prevents tangling of the rope and insures ready access at 60 all times for use of the appliance.

Having thus fully described my invention, what I claim as new and desire to secure by Letters Patent is—

1. The combination with a pair of spaced tracks and carriages supported thereon, of 70 a line arranged in zig zag flights between said carriages and having its ends anchored, said line having a tension flight, and a counterbalancing weight on said tension flight.

2. The combination with a pair of spaced 75 tracks and carriages supported thereon, of a line having anchored ends and arranged in zig zag fashion between said carriages, said line having a plurality of tension flights, 80 pulleys on said tension flights and a journal-bearing frame for the pulleys, and a counterbalancing weight suspended from said frame.

3. The combination of tracks, carriages and hinged yokes with pulleys therein, a line 85 having anchored ends and formed with zig zag flights between said pulleys, guide pulleys and a plurality of tension flights in said line, a frame having pulleys supported on said tension flights, and a weight on the 90 frame.

In testimony whereof I affix my signature.

WALTER J. CUMMINGS.
